UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

RESILIENT SHACKLE.

Application filed August 13, 1923. Serial No. 657,020.

This invention relates to improvements in resilient shackles.

The object of the invention is to provide a simple and relatively inexpensive device 5 adapted to act as a cushioning shackle for buff and draft shocks between vehicles, the arrangement being especially adapted for mine cars.

In the drawing forming a part of this specification, Fig. 1 is a longitudinal, central, vertical section through the adjacent ends of two mine cars showing my improvements in connection therewith. Fig. 2 is a horizontal sectional view corresponding substantially to 15 the broken section line 2—2 of Fig. 1. And Fig. 3 is a vertical transverse sectional view corresponding to the line 3—3 of Fig. 1.

In said drawing, each of the mine cars is shown as provided with a heavy flooring 10 and vertical end walls 11. The flooring is 20 cut away to provide pockets 12 at each end of the car to accommodate the parts of the shackle. Drawbars 13 are also shown on top of the heavy flooring 10, the drawbars being 25 extended outwardly above the pockets 12. Cover plates 14 are also preferably employed as best shown in Fig. 1, the latter being bolted to the flooring of the car and riveted to the drawbars 13.

30 The improved shackle or draft rigging, as shown, comprises, broadly, a yoke A; a second yoke B; a spring C; a block D; and a second block E, together with the usual coupling pins F—F.

35 The yoke A is arranged in a horizontal plane and has side arms 15—15, and a connecting section 16 at one end. At the other end, the block E is rigidly secured to the yoke A by transversely extending rivets 40 17—17, the block E being vertically apertured to accommodate the corresponding coupling pin F.

The other yoke B is arranged vertically and has upper and lower horizontally extending arms 18—18 and an integral connecting section 19 at one end. Near their free ends, the arms 18 are provided with elongated slots 20—20 through which is passed the other coupling pin F. In this connection it will 50 be observed from an inspection of Fig. 1, that lower plates 21 are secured to each of the mine cars and provide lower bearings for the coupling pins F and suitable supports for the resilient shackle.

55 The block D is of rectangular cross-section

and fits between the arms of the yoke A and also between the arms of the yoke B, and is disposed at the opposite end of the shackle to the block E. Said block D is provided with an elongated opening 22 through which is 60 extended the corresponding coupling F.

The spring C is interposed between the block D and the closed end of the yoke B. As clearly shown in Fig. 1, the closed end of 65 the yoke B normally abuts the block E and is perforated to accommodate the guide lug 23 which is extended from the block E, longitudinally of the device, and which is adapted to maintain the yokes A and B on a common longitudinal center line. 70

With the arrangement shown, and particularly as evident from an inspection of Fig. 3, the spring C is substantially completely housed by the four arms of the two yokes A and B and is maintained in proper position by the arms of said yokes. 75

The operation of the device is as follows, assuming a draft action, that is, when the two mine cars are pulled apart. For convenience of explanation, it may be assumed that 80 the right hand mine car will remain stationary and that the left hand car moves toward the left as viewed in Fig. 1. During this draft action, it is evident that the yoke A will be pulled toward the left, thus moving 85 the block D therewith and compressing the spring C between the block D and the end 19 of the yoke B, the latter being held stationary by the coupling pin F on the right hand car. In buff action, that is, when the 90 two cars tend to approach each other, and still assuming that the right hand car remains stationary, the operation is as follows: The yoke A carrying the block E will move toward the right as will also the yoke B. 95 The block D, however, will be held stationary by the corresponding coupling pin F and hence the spring C will be compressed between the block D and the end 19 of the yoke B. 100

In addition to cushioning the buff and draft shocks, as above explained, it will be observed that my improved resilient shackle readily accommodates itself to a pivotal action when the cars are on curved sections 105 of track.

The device shown and described is comprised of relatively few parts, each of which is of simple construction, readily adapting it for manufacture at small cost. Further- 110

more, the entire arrangement is such that it may be readily applied to mine cars now in service without any great expense.

I have herein shown and described what I now consider the preferred manner of carrying out the invention, but the same is merely illustrative and I contemplate all changes and modifications that come within the scope of the claims appended hereto.

10 I claim:

1. In a resilient shackle for mine cars and the like, the combination with a closed yoke adapted to be attached to the end of one car, said yoke being arranged in one plane; of a second yoke arranged in a plane at right angles to the first named plane and looped with respect to the first named yoke, said second named yoke being adapted for slideable connection with the end of the adjacent car; a block slidably attached to said second car; and a spring interposed between said block and the remote end of the yoke connected to the same car.

2. In a resilient shackle for mine cars and the like, the combination with a yoke closed at both ends; of means for pivotally connecting one end of said yoke to one car; a second yoke looped with said first named yoke; means for slidably and pivotally connecting the opposite end of said second named yoke to an adjacent car; and a spring disposed between the arms of said yokes and compressible in either buff or draft action.

3. In a device of the character described, the combination with two vehicles each having rigidly associated means for attaching a resilient shackle thereto; of a closed yoke pivotally connected to one of said attaching means and adapted to swing in horizontal plane; a second yoke pivotally connected to the attaching means of the other car and adapted also to swing in a horizontal plane, both of said yokes being movable in the same direction in buffing action;

a spring disposed between the arms of said yokes and compressible by said yokes in draft action; and means within said yokes and slideable relatively thereof in buffing action to compress said spring.

50

4. In a resilient shackle for mine cars and the like, the combination with interconnected yokes, one extending in one plane and the other in a plane at right angles thereto; of cushioning means disposed within the arms of said yokes; means for fixedly attaching one end of one of said yokes to one car and limiting its movement with respect thereto to pivotal movement; means for slidably connecting the opposite end of the other yoke to an adjacent car, and means connected with said yokes for compressing said spring upon both buff and draft.

55

5. In a resilient shackle, the combination with a yoke; of cushioning means and a follower disposed within said yoke; said yoke and follower being provided with oppositely extending aligned apertures for the reception of a coupling pin; and an oppositely arranged yoke having a portion adapted to bear upon said follower, and another portion arranged to bear upon the first yoke, remote from said follower, said last named portion being provided with an aperture for the reception of a coupling pin.

60

6. In a resilient shackle, the combination with oppositely disposed inter-connected yokes; of cushioning means arranged between the arms of said yokes; and means associated with said yokes operating to compress said cushioning means upon movement of said yokes in unison in one direction and to compress said cushioning means upon movement of one of said yokes relatively to the other.

65

In witness that I claim the foregoing I have hereunto subscribed my name this 9th day of August, 1923.

STACY B. HASELTINE.
